UNITED STATES PATENT OFFICE.

CHARLES W. SAUER, JR., OF ELIZABETH, NEW JERSEY.

AUTOMATIC CIRCUIT-CLOSING DEVICE FOR ELEVATORS.

1,090,794.

Specification of Letters Patent.

Patented Mar. 17, 1914.

Application filed September 16, 1912. Serial No. 720,654.

To all whom it may concern:

Be it known that I, CHARLES W. SAUER, Jr., a citizen of the United States, residing at Elizabeth, in the county of Union and 5 State of New Jersey, have invented new and useful Improvements in Automatic Circuit-Closing Devices for Elevators, of which the following is a specification.

My invention relates to an automatic circuit closing device for use in connection 10 with elevators.

An object of my invention is to provide a circuit closing device which is carried by the frame work of an elevator door, which 15 device normally keeps the electrical circuit open, however, as soon as the elevator door is closed, the circuit will again be closed.

The advantages and novel features of my invention will be manifest. Many serious 20 accidents have occurred in large buildings and department stores because of the fact that elevator conductors almost invariably start the machines before the door is closed. In most cases, the machine is started and 25 the door given a push, and sometimes the elevator is at the next floor before the door below is closed. It is my object to provide this circuit closing device which will prevent the operator from starting the machine 30 until after the door is closed, the circuit being broken and therefore the mechanism of the machine cannot be energized.

With the above and other objects in view, my invention relates to such details of construction and in the arrangement and combination of parts as will hereinafter be 35 fully described and specifically pointed out in the appended claims.

In describing my invention in detail, reference will be had to the accompanying drawings wherein like characters denote 40 like or corresponding parts throughout the several views, and in which the Figure is a side elevation of my invention showing 45 the side plate thereof removed, Fig. 2 a diagrammatical view of the electrical circuit in which switches are connected.

In the accompanying drawings wherein 50 is illustrated the preferred form of my invention, an elevator door, and frame are shown. While this form of door and frame has been illustrated in the drawings, it is to be appreciated that this form is merely shown for sake of illustration and that other 55 devices can be employed if occasion should require.

The numeral 10 designates the casing of the device which is sunk into the frame of the building and which is insulated therefrom as shown at 11. The casing has the 60 ordinary lips 12 provided therein which have openings 13 provided therethrough for the reception of the screws carried by the side pieces 14. A shaft 15 is journaled through the side pieces 14 and has pivoted 65 thereon a substantially bell crank arm 16, the latter having a coil spring 17 connected therewith and with a lug 18. A stop 19, limits movement of the bell crank 16, as shown by the top line position of the latter 70 in Fig. 1.

The forward extremity of the arm 16 has an enlargement 20 provided thereon which has a depression therein for the reception of the contact point 21 carried upon the plate 22, the latter being supported upon a block 23 as is shown. An electrical conductor 24 has connection with the plate 22 and extends through the upper portion of the casing as shown, it being insulated from the latter of the sleeve 25. It is now apparent that when the enlargement of the arm 16 is in engagement with the contact point 21 a circuit will be closed through the shaft 15 and conductor 26, the latter extending from the lower portion of the casing and being insulated therefrom by the sleeve 27. The conductors above referred to have connection with the main line of the elevator and if communication between these 90 two is established, the mechanism controlling the elevator may be operated, however, if the circuit is broken, the operator cannot under any circumstances start the machine.

By the provision of the spring 17, it is 95 apparent that the arm 16 is normally held out of engagement with the contact points 21 and against the stop 19.

For purpose of throwing the arm into engagement with the contact point, the door is provided with a projection 28 which is secured thereto by the pins 29 and insulated therefrom by the strip of insulating material 30.

A finger 31 is pivoted within the casing 105 as shown at 32 and has connection at its lower extremity with a link 33, the latter also being pivoted to the lower extremity of the arm 16.

In the operation of my invention when 110 the door A is open, the mechanism within the casing will attain the position indicated

in dotted lines in Fig. 1, however, when the door is closed the projection 28 carried thereon will engage the finger 31, whereby the arm 16 will be rocked so as to close the 5 circuit between the contacts 24 and 26 as above set forth.

By this arrangement it is thought that the difficulties which have heretofore existed in connection with elevators are obviated.

10 I desire to be understood that I may make slight changes in the construction and in the arrangement and combination of parts, provided, however, such changes fall within the scope of the subjoined claims.

15 Having thus fully described my invention, what I claim as new, and desire to secure by Letters Patent, is:—

1. In combination with a door and door frame, of a casing carried by said frame, 20 said casing having conductors introduced therein, a contact point carried with said casing, a shaft journaled through said casing, said shaft having an arm pivotally mounted thereon, one of said conductors having connection with said arm, a lug positioned within said casing, a coil spring connecting said lug and said arm, whereby the latter is held out of engagement with said contact 25 point, a finger pivoted within said casing, a link connecting said finger and said arm

and means carried by said door frame and engaging said link for throwing said arm into engagement with said contact point as and for the purpose set forth and described.

2. In combination with a door and door frame, of a casing carried by said door frame, said casing having electrical conductors introduced therein, a block supported within said casing, a plate upon said block, a contact point carried upon said plate, one of said conductors connecting with said plate, a shaft journaled in said casing, an arm on said shaft, said arm having an enlargement on one end for engagement with said contact point, a lug positioned within said casing, a coil spring connecting said lug and said arm, normally holding said arm out of engagement with said contact point, a finger pivoted within said casing, a link connecting said finger to said arm, the other of said conductors having connection with said shaft, and a projection carried by said door for engaging said finger and throwing said arm into engagement with said contact point as and for the purpose set forth and described.

CHARLES W. SAUER, JR.
